Patented Nov. 10, 1914.

UNITED STATES PATENT OFFICE.

FRANK BURGNER AND JASPER BURCH, OF SILVER CITY, UTAH.

CLEVIS CONNECTION.

1,116,987.

Patented Nov. 10, 1914.

Application filed August 5, 1913. Serial No. 783,118.

To all whom it may concern:

Be it known that we, FRANK BURGNER and JASPER BURCH, citizens of the United States, residing at Silver City, in the county 5 of Juab and State of Utah, have invented new and useful Improvements in Clevis Connections, of which the following is a specification.

This invention relates to clevis connections, and it has for its object to produce a 10 self locking clevis of simple and improved construction.

A further object of the invention is to produce a clevis connection embodying a 15 hingedly supported bar and a post engaged thereby, said post being notched for engagement with a latch member carried by the hinged bar, the construction being such that the latch member will be relieved from 20 strain.

A further object of the invention is to provide a clevis construction which shall be simple, thoroughly efficient in operation and capable of being easily repaired in case of 25 injury.

With these and other ends in view which will readily appear as the nature of the invention is better understood, the same consists in the improved construction and novel 30 arrangement and combination of parts which will be hereinafter fully described and particularly pointed out in the claims.

In the accompanying drawing has been 35 illustrated a simple and preferred form of the invention, it being, however, understood that no limitation is necessarily made to the precise structural details therein exhibited, but that changes, alterations and modifications within the scope of the claims may be 40 resorted to when desired.

In the drawing, Figure 1 is a side elevation showing the hinged bar raised for the introduction of a link or connecting member into the clevis. Fig. 2 is a longitudinal 45 sectional view showing the clevis member closed upon the link. Fig. 3 is a top plan view. Fig. 4 is a transverse sectional view taken on the line 4-4 in Fig. 2.

Corresponding parts in the several figures 50 are denoted by like characters of reference.

The improved clevis includes a body portion 6 having a forwardly extending base plate 7 and a rearwardly extending neck 8 which may be provided with a threaded 55 socket 9, whereby it may be attached to a connecting rod or the like. Connected with

the body portion 6 by means of a pin or pivot member 10 is a swinging arm or bar 11 having in the underside thereof near its free end a socket 12 which communicates 60 with a longitudinal bore 13 wherein is placed a spring actuated latch member 14 having a button 15 that projects through a slot 16 and whereby the latch member may be retracted against the tension of the 65 spring.

The base member 7 is provided with a female threaded aperture or socket 17 wherein is mounted a post 18, the upper end of which is adapted to enter the recess 12 in 70 the arm 11, said post being provided with a notch 19 for the reception of the projecting portion of the latch member 14 which is beveled, as shown, so as to readily engage the post when the hinged arm 11 is swung in 75 the direction thereof.

It will be readily seen from the foregoing description taken in connection with the drawing hereto annexed, that by retracting the latch member 14, it is disengaged from 80 the notch 19, thus permitting the arm 11 to be swung clear of the post, as seen in Fig. 1, enabling a connecting member, such as a link 20, to be introduced. By swinging the arm 11 in the direction of the post, the latter will engage the recess 12, and the notch 19 will be engaged by the latch member 14, thereby locking the arm 11 securely in position and confining the link or member with which the clevis is to be connected. If tensile strain is exerted on the connecting member 20, such strain will be taken up by the post 18 and will be sustained equally by the base member 7 and by the hinged arm 11, the latch member being subjected to no strain 95 whatever. The post 18 may be readily replaced in case of breakage or injury.

The improved clevis or connecting device may be conveniently used on any kind of machinery where there are clevis connections to be made. It is particularly useful in making brake and gear shifting connections. While the pin or post 18 has threaded engagement with the base plate 7, the outer end of said post is of non-circular 100 cross section, preferably square, the recess 12 being correspondingly shaped, thus preventing the post from rotating and working loose. By the improved device, a connection may be made or broken in a moment's 110 time, and the device is, therefore, decidedly time-saving as compared with ordinary

clevises which require pins, bolts or screws to be adjusted. It will also be noticed that the improved device has no loose parts that are liable to become misplaced and lost.

Having thus described the invention, what is claimed as new, is:

1. A clevis including a body portion, a base member extending forwardly therefrom, an arm hingedly connected with the body portion and having a non-circular recess, a post having threaded connection with the base, said post having a portion of non-circular cross section for engagement with the recess, and locking means for connecting the post with the hinged arm.

2. A clevis comprising a body portion having a forwardly extending base and a rearwardly extending neck provided with a female threaded socket, a post rising from

the base and having threaded connection therewith, said post having an end portion of non-circular cross section, an arm hingedly connected with the body portion and having a recess to engage the non-circular portion of the post, a spring actuated latch member housed in the arm and adapted to engage the post, the latter being notched for such engagement, and means for retracting the latch member against the tension of the spring.

In testimony whereof we affix our signatures in presence of two witnesses:

FRANK BURGNER.
JASPER BURCH.

Witnesses:

EDGAR A. MONTAGUE,
FRANCIS ORTON.
